CONDENSER

John M. Cage, Montclair, N. J., assignor to Cage Projects, Inc., Union City, N. J., a corporation of New Jersey

Application December 1, 1948, Serial No. 62,843

4 Claims. (Cl. 175—41)

1

This invention relates to capacitors for use in electric circuits, as, for instance, high voltage power circuits for television and other similar high voltage applications.

One object of this invention is a new and improved capacitor for high voltage circuits, that is characterized by its small size and its ability to withstand extremely high potentials.

Another object of this invention is a high voltage capacitor wherein extremely long leakage paths are maintained between the terminals thereof, and substantially uniform dielectric fields are maintained over the surface of the dielectric material.

Still another object of this invention is a new and improved capacitor of the character set forth that is economical to manufacture and is adjustable to provide a wide range of capacities.

Another object of this invention is a new and improved condenser, particularly useful in high voltage power supplies for television equipment.

Another object of this invention is a condenser bank for high voltage power supplies that will materially simplify the structure of these supplies, and at the same time materially reduce the formation of corona and breakdown of the condensers due to moisture and dirt settling on the surfaces thereof.

Still another object is a new and improved condenser.

These and other objects of this invention will become more apparent from the following description taken in connection with the accompanying drawings forming a part of this application.

In the drawings, Figure 1 is a cross-sectional view of one embodiment of this invention.

Fig. 2 is a cross-sectional view taken along line 2—2 of Fig. 1.

Fig. 3 is a perspective view of a part of one of the elements of the embodiment in Fig. 1 to illustrate certain details of the structure.

Fig. 4 is a cross-sectional view of another embodiment of this invention.

Fig. 5 is a cross-section of the embodiment shown in Fig. 4 taken along the line 5—5 thereof.

Fig. 6 is still another modification of this invention.

Fig. 7 is a cross-sectional view of Fig. 6 taken along the line 6—6 thereof.

Fig. 8 illustrates still another embodiment.

Fig. 9 is an end view of the embodiment shown in Fig. 8.

Fig. 10 illustrates still another embodiment of this invention.

2

Capacitors at the present time constitute one of the most frequent sources of failure in high voltage power supplies and with the advent of television, and especially television equipment embodying projection type cathode ray tubes using voltages of the order of 20,000 to 30,000 volts, and even higher, the problems of servicing this equipment and maintenance costs are greatly increased.

10 My new and improved capacitor overcomes many of the present difficulties encountered with present capacitors, and at the same time I am able to materially reduce manufacturing costs and produce a condenser somewhat smaller than conventional condensers of equivalent capacities and voltage ratings.

In Figs. 1, 2 and 3, I have illustrated one embodiment of my new and improved capacitor that can be adjusted over a relatively wide range 20 of capacities during the manufacture thereof.

This form of the invention embodies dielectric material between the pole pieces which is formed in two parts, adapted to be abutted one against the other, and spacers, also of dielectric material, 25 may be interposed between these parts to alter the capacity of the finished unit.

More particularly, the condensers consist of a pair of cup-like dielectric elements 10. These elements are preferably circular in shape and provided with plane end walls 10', adapted to be 30 abutted one against the other.

In the present embodiment, I have illustrated a pair of spacers 12 interposed between the surface 10' of the dielectric elements 10 to decrease the capacity of the condensers, and of course at 35 the same time to increase the voltage rating thereof.

The inner surface 14 of the cups 10 is generally spherical in shape, and is preferably coated with a thin layer of silver 16 or other suitable conducting material. I prefer silver because of its non-corrosive characteristics, although under certain circumstances, as will appear hereafter, other materials, such as copper and lead, can also be used. The wall 18 of the cup 10 is preferably extended somewhat beyond the termination of the coating 16 on the spherical part of the dielectric element, to increase the leakage path between the terminals of the condenser, and thereby effect a further increase in operating potential of the condenser. Each element 10 in its finished form resembles generally a plano-concave lens, and when the elements are placed together in the manner previously described, 50 they in effect form a bi-concave structure.

The condenser terminals 20 are each provided with a circular head part 22, having a spherical surface on one side thereof, adapted to contact and be soldered to the silver coating 16 on the element 10, and a rod-like or terminal part 20, formed integrally therewith and extending outwardly for the attachment of wires, or for making suitable connections to the condensers.

The elements 10, together with a part of the terminals 20 are then inserted in a cylindrical housing 26, which extends somewhat beyond the wall 18. The housing is then preferably closed at its ends by the end walls 28, having openings 30 to receive and lend added support to the outwardly extending terminal parts 24.

A particularly good dielectric material for the fabrication of the elements 10, as well as the spacers 12, is titanium oxide, which has a dielectric constant of about 5000-K. The housing 26 and the end walls 28 may also be formed of titanium oxide, although some other dielectric material may also be used.

The dielectric elements 10 and 10' are held in the housing 26 by means of the end walls 28 cemented to the housing 26 and bearing against collars 24' and the terminal parts 24. I prefer to fill the entire unit with a suitable insulating paste such as silicone or the like. The elements 10 and 12 are also preferably held in position by a suitable high dielectric cement.

From the foregoing description of one embodiment of this invention, it is apparent that I have been able to materially increase the leakage path from one terminal to the other because the shortest distance between two terminals 20 is over the external surface of the condenser, and voltage cannot leak from one silver coating 16 to the other over the outer surface of the elements 10.

Furthermore, an electrostatic field produced in a condenser, when a potential is applied thereto, is usually very much greater at the edges of the poles, which in this instance are the silver coatings 16, than at the center. By fabricating the condensers in the manner described, I have provided the thickest part of the dielectric at the edges thereof, so that I am able to obtain a substantially uniform electrostatic field throughout the entire dielectric.

Another advantage of this structure resides in the employment of two individual elements 10 between which can be placed one or more spacers 12 to produce condensers of different values and without involving any material changes in the manufacturing process, and without altering the size or shape of any of the component parts thereof.

Figs. 4 and 5 illustrate another embodiment of this invention to further increase the leakage path over the surface of the condenser.

In this embodiment I have illustrated the elements 10 of Fig. 1 as being formed of one piece and have denoted it in the figure by the numeral 40. I have also illustrated in this figure the outer housing as being formed integrally with the dielectric element 40, and have denoted this housing by the numeral 42. The other elements of the condenser illustrated in this figure are similar to those shown in Fig. 1, and have been indicated by like numerals.

The outer housing 42 is provided with a series of grooves or serrations 44 on the outer surface thereof, with each groove or serration completely encircling the housing. In this way the length of the leakage path over the surface of the con-

denser is increased to approximately twice the distance of a straight line path, and will therefore withstand voltages materially higher than those shown in Fig. 1. This is particularly important in damp and humid climates wherein the component parts of a television set, for example, are in a protected position and are usually at a lower temperature than the surrounding atmosphere. Under these conditions, of course, moisture will readily condense on the parts, and, in the presence of dirt and other foreign matter which settles on the surfaces of these parts, forms a conducting path. By maintaining the conducting path extremely long, as in the present embodiment, the presence of breakdown can be materially reduced, even under adverse conditions. It is, of course, possible to serrate or ridge the outer surface of the housing 26 in Fig. 1 in substantially the same manner as illustrated in 44 in Fig. 4, with the same and desirable and beneficial results.

In Figs. 6 and 7, I have shown another modification of my new and improved condenser, which embodies certain of the advantages shown in Figs. 1 and 4. In this figure the dielectric elements are denoted by the numeral 50 and are cemented in abutting relationship in the outer housing 52 in substantially the same manner as heretofore described in connection with the element 10 in Fig. 1. I have also illustrated in this figure the employment of two spacers 54 interposed between the elements 50. The elements in this form of the invention are provided with end walls 56, having substantially flat inner surfaces 58, on which is deposited a suitable silver or other metallic coating 16. The condenser terminals 60 are each provided with heads 62 having an outer contour resembling that of a toroid, and having a flat surface thereon to abut and be secured to the silver layers 16. This outer housing 52 may, of course, be ridged in the manner shown in Fig. 4, and the ends of this housing are of course preferably closed by end walls 64, cemented to the housing 52. Because of the particular structure of the elements 50, the manufacturing problem may be somewhat simplified and therefore under certain conditions, this structure would be preferred.

In each of the embodiments heretofore described, the layer 16 has been indicated as being a layer of silver. I prefer to apply the silver in the form of a paint consisting of powdered silver suspended in a suitable organic binder solution that can be readily applied in any suitable manner to the desired surfaces.

The painted parts are then preferably baked at a temperature of approximately 800° C. to harden the silver and cause it to adhere to the walls of the element. The terminals of the condenser can then be readily soldered or sweated in place at the center of the silver layer. This method of forming the silver coating and adhering the silver to that coating provides a secure connection, and with the added support provided by the end walls of the housing, a rigid structure is obtained.

To further improve the condenser and reduce corona losses, I prefer to fill the cavities between the end walls of the housings and the inner surface of the elements with a suitable insulating material, such as silicone insulating paste. A silicone is a substance wherein each molecule includes an atom of silicon bonded directly to an atom of carbon.

In each of the previous embodiments of the invention separate end walls are provided for the cylindrical housing to enclose the dielectric elements. In the alternative, the housing and the end walls can be fabricated in one piece, with the housing split circumferentially so that the individual parts or halves can be slipped over the ends of the pole pieces to enclose the condenser and then suitably cemented together to form a unitary structure.

I have illustrated such a structure in Figs. 8 and 9, and have illustrated in these figures cylindrically shaped elements 70, having a pair of somewhat thinner elements or spacers 72 interposed therebetween. The outer surfaces of the elements 70 are again provided with a suitable coating 16, having pole pieces 74 fastened thereto in the manner described in connection with the previous figures.

The outer housing 76, in this modification, consists of two cylindrically shaped cup-like parts 78 and 80. The end walls of these housing parts are relatively thick and are provided with center openings 78' and 80' terminating in inner recesses 79 and 81, respectively, to receive the terminals 74 of the condenser. These housing parts 78 and 80 completely enclose the condenser elements and part of the terminals and may be coated with silicone paste or cemented to the condenser elements by a suitable high dielectric cement. The edges of the housing halves are also cemented together along the line 82 to form a rigid unitary structure. It may also be desirable to cement the terminals 74 in the openings 78 and 80, and to fill the openings between the silver layers 16 and the adjoining face of the housing parts with silicone or other suitable insulating material, which may be in the form of a paste.

This condenser structure is particularly useful in certain types of high voltage power supply circuits wherein two or more of the condensers are connected in series as well as with other components of the power supply. An outstanding example resides in the voltage multiplier type power supply wherein three or more rectifier tubes are connected to a radio frequency power source to both multiply and rectify the voltage. In an application employing say five rectifier tubes, a bank of three series connected condensers, and a bank of two series connected condensers, are employed. In the use of individual condensers in an application of this character, where voltages of as high as 100 kv. are developed, large corona losses are experienced at the terminals of the condensers as well as each condenser must be very well insulated from associated components to prevent any breakdown between the components.

My new and improved condenser lends itself readily to power supplies of this character in that I can arrange two or more of the condensers, connected in series, within a single housing of the insulated material to prevent the collection of moisture and dust about the condenser parts, and in addition I can provide direct connections between the condensers that are free from sharp corners and uneven surfaces, primarily responsible for the generation of corona in high voltage circuits.

Such a structure is illustrated in Fig. 10, which shows three individual condensers, mounted within a single housing, and which may either

be evacuated or filled with a suitable insulating material, such as the silicone paste previously referred to.

The three dielectric elements are indicated in this figure by the numeral 90 and are in the form of bi-concave elements, with the concavity being spherical in shape. Each of the elements 90 is provided with three or more projections 92 extending from the edge thereof to slidably contact the inner surface of the cylindrical housing 94. The elements 90 are each provided with suitable silver coating 16, as previously described in connection with other figures, and are held in spaced relationship within the housing 94 by terminals or conductors 96 interposed between the elements 90. Conductors 96 are each provided with end portions 96' adapted to be soldered or otherwise suitably fastened to the silver layers 16.

At the righthand end of the housing 94 is a short tubular insulating member 98 secured to the end of the housing and having a small projection 100 on its inner end to receive and hold one end of a small spring 102. Between this spring 102 and the adjoining silvered surface of the element 90 is a condenser terminal 104 fastened at one end 106 to the silvered surface 16 and having at its other end the small projection 108 for engagement with the other end of the spring 102. The element 90 farthest to the left is provided with terminal 108 which is suitably fastened to the adjoining silvered layer 16 on the element and has on its outer end a projection 110 of reduced section for engagement with an opening 112 in the end wall 114 on tube 94.

In the assembly of these condensers within the tube the condenser terminals 96, 104 and 108 are first fastened to their respective silver layers with the elements 90 in proper alignment. The structure is then slid into the tube so that the projection 108 of the terminal 104 will engage the spring 102. The end wall 114 of the tube 94 is then fitted over the projection 110 of the terminal 108 and the entire assembly moved inwardly of the tube to compress the spring 102. The end wall 114 may then be suitably fastened to the tube 94 by glass welding or by applying a suitable cement to the edge thereof.

Connections for the several condensers are made through the wires 116 fastened to the condenser terminals 96, 104 and 108. These connections are brought through openings 118 in the wall of the tube 94. As the condensers are assembled within the tube and the leads 116 are brought out through the openings 118, the openings are then closed by applying a cementing compound, or by melting glass about the wires 116 at the points where they emerge from the tube 94. In this way a completely sealed unit is obtained that will be relatively unaffected by moisture and foreign matter on the outer surfaces thereof.

If desired, the openings 118 in the tube 94 can be staggered about the circumference thereof in order to increase the leakage path between the terminals and also to provide shorter leads between the components of the power supply.

From the foregoing description it is apparent that the condenser structure can be evacuated by any conventional process, or, in the alternative, it may be completely filled with a silicone insulating paste or other similar insulating material and then sealed against the admission of moisture or other foreign matter.

In each of the embodiments of this invention I

have described the several elements as being generally cylindrical in shape. It is apparent, however, that the important advantages of this invention can be realized with the elements formed in other ways. For instance, the elements may be generally square or rectangular in shape and may be encased in suitable square or rectangular housings. It is also to be understood that certain other modifications and changes can be made in the embodiment herein illustrated without departing from the true scope of this invention. Furthermore, the concavities of the elements may be parabolic or have other contours and the outer surface of the tube 94 in Fig. 10 may be ridged similar to the outer housing of the embodiment shown in Fig. 4.

Certain of the matter disclosed herein is disclosed and claimed in an application filed by applicant on February 6, 1951, Serial No. 209,563.

I claim:

1. A condenser comprising a housing of dielectric material, a pair of terminals each having one end thereof extending from the housing, the inner ends of said terminals being separated by a pair of dielectric elements adapted to be placed in overlying relationship one with the other, conductive surfaces on the outer side of each element for the attachment of its respective terminal and spacer means interposed between said elements for fixedly adjusting the capacity thereof.

2. A condenser according to claim 1 wherein said elements are cup-shaped.

3. A condenser comprising a cylindrical hous-

ing of dielectric material, a pair of plano-concave dielectric elements in said housing with the plane surfaces in overlying relationship, a conductive coating on the concave surface of each element, dielectric spacers between said overlying surfaces of said elements to separate said elements, and metallic terminals secured to said conductive coatings.

4. A condenser comprising a cylindrical housing of dielectric material, a pair of plano-concave dielectric elements in said housing with the plane surfaces thereof in overlying relationship, and conductive terminal means placed against and conforming with the concave surface of each element, said elements being adapted to receive dielectric means interposed between the overlying surfaces to hold them in spaced relationship.

JOHN M. CAGE.
